UNITED STATES PATENT OFFICE

156,439

TABLE BASE

Harry Lebansfeld, New York, N. Y., assignor to United Industrial Syndicate, Inc., New York,
N. Y., a corporation of New York

Application October 29, 1948, Serial No. 149,381

Term of patent 14 years

(Cl. D33—14)

To all whom it may concern:

Be it known that I, Harry Lebansfeld, a citizen of the United States, residing at 1934 Ocean Parkway, city of New York, county of Kings, and State of New York, have invented a new, original, and ornamental Design for a Table Base, for which the following is a specification, reference being had to the accompanying drawing, forming part thereof.

I claim:

The ornamental design for a table base, substantially as shown.

HARRY LEBENSFELD.
